US0D1110921S

(12) **United States Design Patent** (10) Patent No.: **US D1,110,921 S**
(45) Date of Patent: ** Feb. 3, 2026

(54) **OAR**

(71) Applicant: **Johan Michiel Verheij**, Brouwershaven (NL)

(72) Inventor: **Johan Michiel Verheij**, Brouwershaven (NL)

(**) Term: **15 Years**

(21) Appl. No.: **35/523,605**

(22) Filed: **Dec. 6, 2024**

(80) **Hague Agreement Data**

Int. Filing Date: **Dec. 6, 2024**

Int. Reg. No.: **DM/243175**

Int. Reg. Date: **Dec. 6, 2024**

Int. Reg. Pub. Date: **Jan. 17, 2025**

(30) **Foreign Application Priority Data**

Jun. 9, 2024 (EM) 015063057-0001

(51) **LOC (15) Cl.** **12-06**

(52) **U.S. Cl.**

USPC **D12/215**

(58) **Field of Classification Search**

USPC D12/215, 214, 317
CPC B63B 1/00; B63H 16/04; B63H 2016/046
